UNITED STATES PATENT OFFICE.

EDDY T. McKAIG, OF CHICAGO, ILLINOIS, ASSIGNOR TO ANTON TRINI, OF CHICAGO, ILLINOIS.

ARTICLE-PACKING MACHINE.

Application filed August 31, 1925. Serial No. 53,590.

My invention relates to improvements in machines for packing articles in cartons or boxes and has special reference to the packing of merchandise such as food products, etc., which are usually enclosed in relatively large light weight packages and packed in cartons made of paper board and having hinged closure flaps.

This present invention is an improvement upon the inventions described and claimed in my copending applications Serial No. 589,799 and Serial No. 702,247 and has special reference to improvements in flap holding devices, in carton or box control mechanisms, in means for assembling the packages into a layer and projecting a layer at a time into the container, and in means for removing the filled carton from the machine.

A particular feature of this present invention relates to the assembling of the packages in a layer containing plurality of rows and means controlled by each row of the approaching packages for automatically stopping the packing mechanism upon failure of any row of packages. This ensures that every layer is a full and complete layer before it is inserted into the container.

Other features relate to novel means for controlling some of the closure flaps of the container, means for supporting the container and for dropping it step by step to receive the several layers, means for projecting a layer of packages into the container, novel means for guiding the container as it descends and is filled and for opening said guiding means to permit the escape of the filled containers.

Other features relate to a simple easily operable clutch for use with the automatic starting and stopping mechanism and which clutch is also capable of manual operation, and to a novel friction clutch through which power is applied to operate the machine and which upon the forced stopping of the machine will give an audible signal.

An important feature relates to the novel layer inserting means which permits the continued assembly of succeeding layers as the preceding layers are being inserted into the container.

My invention will be more readily understood by reference to the accompanying drawings forming part of this specification, and in which:

My improved packing machine is adapted to pack wrapped packages or boxes such as 110

those in which breakfast foods, soap chips, etc., are enclosed for sale. Such packages are often relatively large and of relatively light weight and these conditions involve 5 certain problems which require special developments to meet them. This present machine is adapted for receiving the output from two wrapping machines carried to the machine in two lines of the packages and to 10 pack such packages in large cartons or boxes in a plurality of layers each containing a plurality of the packages. The machine is especially adapted or arranged for packing the packages 1, illustrated in Fig. 20 into 15 the cartons or boxes 2, illustrated in Fig. 21. The cartons 2 are made of heavy cardboard or corrugated paper board and are provided with attached closure flaps such as 3 and 4 which have to be held back out of the way 20 while the cartons are in the machine. The machine is provided with a vertical chute 5 down which the boxes 2 move past the packing mechanism designated generally by 6.

The articles or packages to be packed are 25 delivered to the packing mechanism 6 by a conveyor belt 7 which is trained around a conveyor roller 8 mounted in suitable bearings on the frame of the machine. The packages 1, as best shown in Fig. 4, are 30 shown as being delivered to the packing mechanism in two parallel lines, and in a direction to move forward through the packing mechanism into the cartons 2, passing down the chute 5.

35 The machine is equipped with simple means for lowering the boxes 2 down the chute step by step for receiving the several layers, with means for dividing off from the streams of packages, delivered to the machine, sufficient of the packages for forming 40 each layer and moving them forwardly into the box, with automatically operable means for stopping the machine upon the failure of either of the lines of approaching packages, and automatically starting the machine 45 again upon the completion of the lines of packages and with many subsidiary co-ordinated features whereby I am enabled to fill and deliver two of the cartons 2, each with 50 30 packages, each minute. In other words I am enabled to pack 3600 packages an hour.

I will first describe the movement of the carton 2 into, through, and out of the machine. 55 Connecting with the upper end of the chute 5 is a horizontal chute 9 into which the cartons 2 are first placed. The closure flaps 3 and 4 are first swung back against the sides of the box to provide an open side 60 10 to be presented to the packing mechanism 6 as the carton descends the chute 5. The outer end 11 of the chute 9 is open and part of the front wall 12 is cut away as shown in Fig. 2 to permit the easy entrance 65 of the carton into the chute 9 by the opera-

tor with the forward flap 4 turned back and the top and bottom flaps 3 turned back. The rear flap 4 of the forward carton in the chute 9 is swung back and held back by the following carton and the forward flap 4 70 of the following carton is held back for a time by the preceding carton.

The control of the top flap 3 as the carton descends the vertical chute is fully described and claimed in my said earlier application 75 Serial No. 589,799. The forward flap 4 is held back on the carton in the horizontal chute 9 by the preceding carton which is descending the vertical chute 5 until the preceding carton drops below the floor of the 80 horizontal chute 9. In order to hold back the forward flap 4 after the preceding carton has dropped below same and during the time that the following carton is being entered into the top of the vertical chute I 85 provide a swinging lever or rod 13 pivotally mounted at its upper end at 14 to hang like a pendulum and its lower or free end 15 arranged to swing to the left, Fig. 2, into contact with the forward flap 4 of a following carton before the preceding carton has dropped far enough to disengage same. As the following carton is pushed into the upper end of the vertical chute 5 the lever 13 90 swings over to the right, to permit this movement, to the position shown at 15' permitting the carton to drop down the chute 5.

This flap holding lever is overbalanced slightly by the weight 16 to cause it to swing to the left as soon as it is released by the 100 carton dropping down the chute 5.

Each carton 2, is free in the chute 5, to drop down and is supported by the preceding carton until the preceding carton has been filled and is discharged from the machine. I provide simple means for supporting the cartons at the proper heights relatively to the packing mechanism to receive the several layers therefrom. For supporting the carton to receive the first layer I 105 preferably provide means for supporting the carton at the back and at the front. This support means comprises a horizontal bar 17 at the rear of the machine provided with two depending rigid arms 18, having inwardly or hooked lower ends 19 adapted to enter into the rear of the chute 5 into the path of the descending cartons, and as best shown in Figs. 8 and 9 engage beneath the rear edge of the carton 2. I also provide a cross bar 20 at the front of the chute 5 upon which are rigidly mounted two upwardly projecting arms 21 bent at their free ends 22 to extend horizontally. These arms are inclined inwardly so that they are normally 110 within the path of the cartons and in such position that the horizontal ends 22 engage beneath the forward edges of the cartons 2. At the time that the carton rests at its bottom rear edge upon the hooked projections 115 120 125 130

18 it also rests at top front edge upon the projections 21. When held on said projections the carton is positioned, in relation to the packing mechanism, to receive the first 5 layer of packages. Rigidly connected with the cross bar 17 is a depending arm 23 which carries a projecting pin 24. A slotted link 25 engages the pin 24 and the opposite end of the link is pivotally connected with a 10 swinging lever 26 at 27 pivotally mounted between its ends at 28 on a side wall of the chute 5. The upper end 29 of the lever 26 is connected by a short link 30 to the upper end of an arm 31 rigidly connected with the 15 cross bar 20 and extending upwardly therefrom. When the lower end of the lever 26 is swung back to withdraw the hooks 19 the projections 21 are simultaneously swung forwardly out of the chute, shown in dotted 20 lines to permit the carton with its first layer to drop. For supporting the cartons 2 at the proper heights to receive the successive layers after the first and for permitting them to drop after each layer has been inserted 25 I provide a pair of vertically movable bars 31' (Figs. 3 and 8) rigidly mounted at their rear ends on a horizontal shaft 32 which is mounted in suitable bearings on the end of a swinging arm 33 which in turn 30 is mounted at its lower end on a cross horizontal shaft 34 carried in suitable bearings on the frame of the machine. The swinging arm 33 has an upwardly extending rigid projection 35 which is adapted to be engaged by 35 a pin 36 projecting out from a crank arm 37 rigidly mounted on a rotatable shaft 38 mounted in suitable bearings on the frame of the machine. For each revolution of the shaft 38 the upper end of the swinging arm 40 33 is swung forward and the shaft 32 with the vertically movable bars 31' are swung or pushed forward. For returning the several parts of this construction to the normal rear position I provide a torsion spring 39 Fig. 45 16 which engages the hub 40 of the arm 33 at one end and a collar 41 at the other end. The sleeve 41 is adjusted on the shaft 34 to adjust the tension of the spring 39. The return action of the spring is limited by an 50 adjustable stop 42 Figs. 3 and 8 which engages with the upper side of a forwardly projecting arm 43 rigid with the swinging arm 33. I preferably provide a rubber bumper 44 on the stop 42. The vertically 55 swinging bars 31' which with the shaft 32 form a frame are swung up by means of a balance weight 45, see Figs. 1, 3, and 4 which is attached to a cable 46 wound around a suitable pulley 47 rigidly mounted on a 60 transverse rotatable shaft 48 carried in suitable bearings on the rear wall of the chute 5. The shaft 48 carries other pulleys 49 one at each side and rotatable with the shaft. Each pulley 49 carries a cable 50 which is attached at its free end to one of the vertically 65

swinging bars near its forward or free end. Preferably the cables 50 are trained over idler pulleys 50' to bring them into suitable alignment with the free ends of the bars 31', as best shown in Fig. 3. As the vertical 70 movement of the bars 31' is more than can conveniently be accommodated by a direct action of the balance weight 45 I provide the arrangement described so that the weight cable 46 can wind up on the pulley 47. For 75 the actual carton supporting member I mount a transversely extending support member 51 in the free ends of the vertically swinging bars 31'. This support member consists of a rod 52 extending across the 80 chute 5 and through slots 53 in the free ends of the bars 31'. This rod is suitably held against endwise movement and carries an antifriction roller 54 which extends across the chute 5 between the side walls thereof. 85 This rod 52 with its roller 54, as best shown in Fig. 9, is moved up into contact with a carton 2 when the same is in position to receive the first layer of packages. Just as the first layer is completely entered the projection 36 on the crank arm 37 (see Fig. 8) engages the arm 35 and pushes the two bars 31' forward. One of said bars 31' has a rigid projection 55 near its free end (see 90 Figs. 3 and 9) and so located that when the bars 31' reach the upper limit of their movement it rises behind the lower end 56 of the vertical lever 26 and in position to push said lower end forward when the bars 31' are 95 pushed forward by the pin 36. This forward movement of the lower end of the lever 26 withdraws the carton supports 18 and 21 and permits the carton with its first layer of packages to rest upon the support roller 54. 100 The carton with the first layer of packages 105 is heavy enough to overcome the counter-balancing effect of the weight 45 and depress the bars 31' until stopped by support devices to be described. The side walls 56' of the chute 5 each have a substantially vertical 110 slot 57 in which the ends of the support rod 52 are guided in their up and down movements.

The slots 53 in the free ends of the bars 31' through which the support rod 52 projects 115 allows the bars 31' to be moved back and forth to release the cartons and let them drop. For supporting the cartons at the various heights to receive the successive layers after the first, I provide a series of abutments 58 on each side of the chute 5 having ends 59 normally projecting in alignment with the slots 57 and in position to receive and support the rod 52 at the desired height. Each of these abutments 58 is pivotally 120 mounted at its lower end on one arm 59' of a bell crank as best shown in Fig. 13 to swing in a vertical plane. The bell crank is pivotally mounted at 60 upon the side wall of the chute and its opposite arm 61 depends and 125

130

is adapted to be engaged by the point of a screw 62 adjustably mounted in a fixed bar 63 for adjusting the position of the bell crank to accurately adjust the height of the support bar 52 at the various heights desired. The abutments are yieldingly held in position in alignment with the guide slots 57 by tension springs 64 which connect at one end with a depending projection 65 rigidly 10 with the pivoted end of the abutment block 58 and at the other end with a pin 66 rigidly projecting from the arm 61 of the bell crank. For causing the abutments to properly align with the slots 57 I provide an abutment bar 15 67 mounted on the side wall of the chute one at each side just behind the slots 57 and curved to conform with the slots and against which the springs 64 yieldingly hold the free ends of the abutments 58. The springs 20 64 obviously also hold the bell cranks against the adjustable screws 62.

The first revolution of the shaft 38 after the first layer has been inserted into the carton releases the carton from the supports 25 18 and 21 and the carton forces the support rod 52 down upon the first pair of support abutments or dogs 58. Obviously the bars 31' are carried down with the rod 52.

Each bar 31' has a rigid shoulder 68 30 formed by the forward end of a block 69 rigidly mounted on the side of the bar 31'. The shoulder is arranged beneath the slot 53 and in position to engage the abutment blocks 58 above their pivoted ends and swing 35 the abutments back and permit the support rod 52 to drop to the next pair of abutments. After the first layer of packages has been inserted and the carton has been dropped upon the first pair of abutments the action 40 just described occurs once for each revolution of the shaft and the packing mechanism is coordinated therewith so that it occurs once for each layer inserted.

When the carton is filled the support rod 45 52 is released from the lowermost pair of abutments and the filled carton drops down upon a conveyor belt 70 (see Fig. 10) by which the filled carton is carried away from the machine. To ensure the discharge of 50 the filled carton from the machine and its delivery to the conveyor I provide a pair of conveyor chains 71 arranged beneath the inner or open side of the carton and adapted to receive the same when it drops down upon 55 the conveyor 70. The chains 71 are provided with carton engaging projections 72 arranged to engage the lower edge of the open side of the carton and push it out of the chute 5. I preferably arrange the lowermost position of the support rod 52 so that 60 the filled carton is supported at such time upon the support roller 54 slightly above the conveyors and consequently it can be moved quite easily out of the chute 5. The mechanism is so timed that the filled carton is out

of the chute 5 before the succeeding carton drops after the insertion of the first layer.

The lower flap 3 on the carton might swing forward into vertical position upon its release from the preceding filled carton 70 and in order to ensure that this flap will be folded back again beneath the carton as it drops down to be discharged I provide swinging guides 73 mounted on a cross shaft 74 at the bottom of the chute 5 and extending in an upwardly inclined position beneath the open side of the carton as the same descends the chute and in position to engage the lower flap 3 and cause same to be swung back beneath the carton. In order to permit the carton to drop down upon the conveyors the guides 73 are yieldingly held up by a tension spring 75 extending between an arm 76 rigidly carried by the shaft 74 and a projection 76' rigid with the frame of the 80 machine. The guides 73 are limited in their upward movement by engaging with the wall of the chute 5.

It will be obvious that the rear wall of the chute 5 must be free to permit the filled 90 cartons to be pushed out, but in order to prevent the premature escape of the lower part of the carton as it descends the chute I provide guards 77 at the two sides of the chute at the rear lower end of same which close in 95 to engage the bottom of the carton as it descends. These guard strips or plates 77 (as shown in Fig. 5) and rigidly mounted on the free ends of arms 78-79 adjacent to the upper and lower ends of same and which arms are pivotally mounted at their opposite ends on the side walls of the chute 5, to swing out horizontally and thus carry the guards 77 out side ways, as shown in dotted lines Figs. 3 and 5, to permit the discharge 100 of the filled cartons. These guard strips are yieldingly held inwardly by tension springs 80 connected between a part of the chute and a projection 81 rigid with the lower hinge bars 79. To force these hinge bars 78 and 110 79 to swing outwardly against the closing action of the springs 80 I provide vertically extending bars 82 Figs. 3 and 15 one at each side and arranged beneath the outer ends of the hinge bars. Each of these bars 82 is carried by an upper bar 83 and a lower bar 84 pivotally mounted on the side walls of the chute 5 between their ends. The bars 82 link the forward ends of the upper and lower bars together and the rear ends of these pivoted bars extend across the path of the support rod 52 and are each adapted to be engaged by said rod 52 as it approaches the upper and lower limits respectively of its movement. When the support rod 52 approaches the lower limit of its movement, as best shown in Fig. 3, it engages the rear end 85 of the bar 84 and swings it down thereby moving the vertical bar 82 upwardly. On the lower end of the bar 82 there is 120 125 130

fixed a longitudinal wedging projection 86 adapted to engage beneath the forward end of the hinge bar 79 and swing same outwardly sufficient to swing the attached guard strip 77 out of the path of the carton as it leaves the chute 5. The contacting surface or edge of the projection 86 has an inclined part 87 and a straight part 88 adapted to retain said guards in open position until the support bar 52 is released and is moved up to its upper position where it engages beneath the rear ends of the upper hinge bars and moves them up thus moving the bars 82 downwardly and withdrawing the wedging projections 86 from beneath the lower hinge bars and permitting the springs 80 to close the guards.

As the carton is nearly filled its top wall has a tendency to sag down and it might drop so low as to hinder the free insertion of the last layer of packages. To prevent this action I provide means for holding up the top wall at the time of the insertion of the last layer. This means comprises depending flat bars 89 (see Figs. 1 and 10) rigidly mounted at their upper ends upon a horizontal bar 90 extending across the open face of the chute 5. The lower free ends 91 of the bars 89 are bent inwardly and are adapted to project into the chute 5 in the path of the descending cartons.

The cross bar 90 is pivotally mounted at its ends on the side walls of the chute 5, at 92 to swing on a horizontal axis to move the hooked ends 91 out of and into the chute as shown in dotted and full lines in Fig. 10. In said Fig. 10, a carton is shown as receiving the last layer of packages and the top wall of the carton is held up at the open side of the carton, as shown in full lines.

Immediately after the last layer is inserted the holding hooks 91 are withdrawn to permit the filled carton to drop freely. To effect this withdrawal of the hooks one end of the bar 90 is provided with a rigid depending arm 93 which is connected by a short horizontal link 94 to the upper end 95 of a vertical lever 96 pivoted between its ends at 97 to the side wall of the chute 5. The lower end 98 of the lever 96 extends down toward the lower end of the chute 5 and at a point coincident with the position of the rods 31' when they are ready to knock out the lowest pair of supporting dogs 59, it is provided a striking plate 99. This plate is pivotally mounted between its ends on the bar 96 at 100. The plate 99 is elongated and is adapted normally to lie substantially horizontal. Its rear end 101 is adapted to be engaged by a pin 102 projecting from the side of one of the bars 31' as the bars 31' move forward to throw off the last pair of support dogs 59 after the insertion of the last layer of packages. This engagement swings the lower end 98 of the lever 96 for-

wardly and thereby withdraw the hooks 91 from beneath the top wall of the filled carton and the timing is such that this occurs just in advance of the dropping of the filled carton.

As the bars 31' drop down after knocking out the next to the lowest pair of support dogs 59, to the position shown in Fig. 10, the pin 102 might hit the plate 99 and not drop down far enough particularly as the bars 31' at this instant may not yet be drawn back for the next forward stroke. To avoid such premature action I pivotally mount the plate 99 so that if its rear end 101 is struck by the descending pin 102 it is free to swing down. The plate is over balanced, its forward end 103 being the heaviest so that as soon as the bars 31' are drawn back for the next stroke forward, the plate 99 drops back again to its normal position which is determined by a stop 104 rigid with the plate 99 and adapted to contact with the forward edge of the bar 96.

As the bars 31' drop down away from the plate 99 immediately after the withdrawal of the hooks 91 the hooks might swing into the chute again before the next following carton has dropped far enough to let the hooks swing into the open side thereof that is they might swing in below the lower wall of the next following carton and thus prevent it dropping down in position to receive its first layer. To prevent this action I provide simple latch means for positively holding the hooks 91 out until the bars 31' are released from the filled carton and rise to their uppermost positions again. This latch means consists of a horizontal latch member 105 Fig. 1 pivoted at one end to the bar 96 near its upper end and provided at its free end with a downwardly extending projection 106 adapted to drop into a notch 107 when the upper end of the bar 96 is swung to the right, Fig. 1, to swing out the hooks 89 by the contact of the projection 102 with the plate 99 when the bars 31 move forward to release the lowermost pair of support dogs 59. This latch holds the bar 96 in position with the hooks 89 swung out until the bars 31' are released by the discharge of the filled carton from the machine and they are permitted to rise to their uppermost position. As the bars 31' approach their uppermost position one of them contacts with a trip bar 108 pivotally connected with the outer end of the latch bar 106 and freely depending therefrom. The trip bar has its lower end 109 bent to form an extension of suitable length so that the bar 31 will lift it sufficiently to unlatch the bar 106 and let the bar 96 swing back to insert the hooks 89. When the bars 31 have reached their upper position the next succeeding carton has dropped to position to receive the first layer of packages and con-

125
130

sequently the hooks 89 drop into the open side thereof in position to engage the upper wall of the carton when the carton descends to a position to receive the last layer of packages.

The packing mechanism 6 which is arranged in front of the chute 5 is provided with an anti-friction bed along which the packages 1 are moved forwardly into the 10 cartons when they are delivered from the conveyor 7. This anti-friction bed comprises a number of parallel horizontal rollers the end ones 110 and 111 being operatively joined by a chain 112 Fig. 9 and the intermediate rollers 113 being all driven in a direction to cooperate with the packing mechanism to move the packages quickly and easily into the cartons. As shown in 15 Figs. 5 and 6, there are two of the endless chains 112 one at each side. I provide a transverse bar 114 carrying an anti-friction roller 115 secured to the two chains 112 by suitable connecting brackets 116 (Fig. 8) and extending across parallel with the series 20 of rollers. This bar is adapted to engage the packages 1 and positively push a layer into the chute 5 for filling the cartons. There is but one of these pusher bars 114 on the chains 112 and each time the bar 25 moves toward the chute or forward it carries a layer into the chute, and while it is moving back again to engage the next layer the carton is dropped in position to receive the next layer. Preferably these 30 rollers are hollow, that is they are pipe rollers, they are therefore light in weight and do not hinder the quick stopping and starting of the packing mechanism. I provide a receiving roller 117 close to the delivery end of the delivery conveyor. This receiving roller and the intermediate rollers 113 are driven by a drive chain 118 which is trained around suitable toothed 35 wheels 119 at the ends of said rollers and around a similar toothed wheel 120 at the end of the chain and in order to obtain suitable contact of the chain with the wheels on the intermediate rollers I provide idlers 121 adapted to be depressed between the 40 chain wheels on adjacent intermediate rollers 113 (see Figs. 3 and 8) and by this means the rollers are all driven in the same direction. As indicated in Fig. 4, the series of rollers which form a receiving platform 45 50 are long enough to accommodate a plurality of rows of the packages 1, in this instance two rows.

While the machine may be driven by any suitable means I prefer to provide a suitable 55 electric motor 122 mounted on the frame of the machine beneath the packing mechanism. The shaft 123 of the motor is coupled to a short drive shaft 124 by a suitable self aligning coupling 125. The shaft 60 65 124 carries a toothed pinion 126 which

meshes with a gear wheel 127 rotatably mounted on a transverse shaft 128 which extends across the machine and at its opposite end carries a toothed wheel 129 which receives a drive chain 130 trained around a similar toothed wheel 131 on a sleeve 132 rotatably mounted on the shaft 133 of the forward anti-friction roller 110. I provide a novel clutch means for rotatably connecting the sleeve 132 with the shaft 133 70 which will be described later. The shaft 133 extends across the frame of the machine and carries at its opposite end a toothed wheel 134 which receives a drive chain 135. One side of the chain 135 is 75 trained around a wheel 136 by which the short delivery conveyor chains 71 are driven. This chain 135 is also trained around a suitable wheel (not shown) at the outer end of the delivery conveyor and by which 80 it is driven. The shaft 38 which carries the projection 36 is driven in suitable timed relation to the filler bar 114 by a pinion 137 on the shaft 137' which carries the feed roller 111, and meshing with a gear 138 85 on the shaft 38. The arrangement is such that the shaft 38 makes one revolution for each complete forward and back movement of the filler bar 114.

I provide friction clutch means for operatively connecting the gear wheel 127 to the shaft 128 whereby should anything occur which would prevent the operation of the machine this connection will give and allow the motor to run without damage to the machine. As best illustrated in Fig. 11, this friction clutch means consists of two friction disks 139 one on each side of the gear. The shaft 128 carries a fixed friction disk 140 at one side and a movable friction disk 141 at the other side of the gear 127 and a spring 142 adapted to bind the gear 127 between the two friction disks. The spring 142 is adjustable by means of the nuts 143 on the shaft 128. By properly adjusting the spring the clutch can be made to transmit sufficient power to run the packer unless it becomes blocked in some manner, then it will slip. In order to call the attention of the one in charge of the machine that it is not running when the friction clutch slips I provide an audible signal consisting of a flat spring 144 secured to the outer face of the flange 141 and projecting beyond the periphery thereof and adapted to engage an inclined projection 145. On movement of the flange 141, which rotates with the shaft 128 to which it is keyed, the gear standing still, the spring is raised by the projection 145 and when it leaves it, it snaps down again thus making a clicking noise.

As explained before I provide means for stopping the operation of the machine upon the failure of either of the lines of approaching packages so as to ensure that every layer 130

of packages inserted in the carton shall be complete. This means comprises a clutch mechanism for rotatably connecting the chain wheel 131 to the shaft 133, see Fig. 17, 5 and disconnecting it from the shaft and I provide means for controlling this clutch manually by the operator and also automatically by the approaching packages. This clutch means comprises a collar or disk 146 10 preferably keyed upon the hub 147 of the chain wheel 131 by means of a plurality of key projections 148 on the hub and similar key ways in the hub of the disk. The disk is slideable from and toward the gear and between the gear at one end and a flange 149 15 fixed on the outer end of the shaft 133. The flange 149 carries two diametrically positioned driving projections 150 and the flange 146 carries two similar and cooperating driving projections 151. The movement of the flange endwise of the shaft 133 is sufficient to engage and disengage said driving projections. For shifting the flange 146 along the shaft to operatively clutch and unclutch 20 the shaft 133 to the chain wheel 131, I provide a radially projecting pin 152 on the outer edge of the flange and a shiftable yoke 153 having two oppositely projecting inwardly extending projections 154 and 155 25 adapted to be positioned to engage the pin 152. The projections 154 and 155 are provided with oppositely inclined pin engaging surfaces 156 and 157 respectively which are effective to move the flange 146 longitudinally of the shaft 133 alternately in opposite directions. The rotation of the gear wheel 131 and consequently of the flange 146 30 is in the direction of the arrow on Fig. 19. The yoke 153 is rigidly mounted on a horizontal bar 158 suitably mounted on the frame of the machine to move back and forth transversely of the shaft 133 for the purpose of moving the projections 154 and 155 alternately into the path of the projection 152. 35 The shaft 158 extends back and carries a compression spring 159 mounted thereon and interposed between a head 160 thereon (see Fig. 1) and one of the brackets 161 in which the shaft 158 is slidably mounted. The spring normally retains the shaft moved to the right, Fig. 1, that is with the driving flange 146 moved to the right, Fig. 18, that is in driving position. For automatically 40 disengaging the clutch I provide a shaft 162 extending across the machine above the path of the packages and mounted in suitable bearings to be oscillated. At one end in alignment with the shaft 158 this shaft 162 carries a dependent arm 163 provided on its lower free end with a head or pad 164 adapted to contact with the head 160 on the shaft 158. If the arm 163 is swung to the left, Fig. 1, it will move the shaft 158 to the left 45 against the spring 159 and disengage the clutch in the manner already described. The shaft 162 carries an arm 165 rigid therewith and projecting out over the approaching line of packages, preferably near the outer edges of one of the lines of the packages. Should the packages fail the arm 165 will 50 not be supported in operative position but will drop and disengage the clutch. At the opposite side is a second arm 167 carrying one of the support wheels 166 but mounted rigidly on a sleeve 168 through which the 55 shaft 162 passes and which sleeve carries a second arm 169 similar to the arm 163 and also adapted to move the shaft 158 endwise to disengage the clutch. In this manner both lines of packages control the machine 60 so that if either line fails the machine is stopped.

In addition to this automatic control I provide a hand lever 170 mounted on the side of the frame and having a handle 171 standing up in convenient position for the operator. The lever carries a projection 172 adapted to engage one of the arms depending from the automatic control. The lever is movable back and forth through a bayonet shaped slot 173 provided in a guide plate 174 fixed on the frame of the machine and a spring 175 is carried by the lever which forces it sidewise into the widened part 176 of the slot 173 when the lever is swung forward and whereby the lever is retained in machine stopping position until released manually from such position see Figs. 1, 22 and 25. 65

In packing packages which are relatively light in weight into the cartons or boxes it sometimes occurs that the boxes do not always remain as positioned but tend either to drag back out of the box or to be tipped up out of true level position or assume other positions not desired. To position the packages accurately and positively and retain them definitely in their proper positions in the carton there is provided power 70 actuated and timed means for cooperation with the packing bar 114 for controlling the packages. 75

To prevent the packages which are already packed from interfering with the insertion of the next succeeding layer there is provided a package guide 177 in the form of a flat plate which rides back and forth on the rollers 113 see Figs. 4 and 23. This guide has vertical side flanges 178 between which the rows of packages are received and by which the packages are engaged with a slight frictional engagement. These side flanges are long enough to extend back to the receiving end of the machine even when the guide is moved forward to its forward limit in the packing operation. The rear portions 179 of these side flanges are made laterally yielding and their extreme rear ends 180 are slightly curved outwardly so 80 that the entering packages can easily enter 85

90

125

130

between these sides and spread them apart. The bottom of this guide member is cut away back of its forward edge to provide a central flat tongue 181 and two side bottom parts 182 and the rollers 113 are cut away to provide grooves to receive these parts so that the top surface of the bottom of the guide is not above the tops of the rollers as otherwise the packages might catch on the rear ends or edges of the parts of the guide.

In Fig. 8, the guide 177 is shown in its rearmost position and in this position it becomes filled with the advancing packages during the time that the pusher bar 114 is moving back to its rear position from its forward position. The sides 178 of the guide are provided with shoulders 183 which, when the guide is at its rear limit are in position to be engaged by the pusher bar 114 as it begins its forward movement. To hold the guide 177 down upon the rollers 113 each side 178 is provided with a laterally extending guide pin 184 which enters a horizontal slot 185 in a rigid guide bar 186 one at each side of the machine.

The guide 177 is carried forward by the push bar 114 with the layer of packages being inserted into the box or carton and the forward end of the guide 177 passes easily over the preceding layer of packages without disturbing them. As the pusher bar 114 begins to travel down at the forward limit of its travel it slides down off of the shoulders 183 and the guide 177 is free to move backward out of the box and deposit the inserted layer of packages therein.

To prevent the backward movement of the guide 177 dragging the packages back with it out of the box a stop plate 187 is provided secured to the lower end of a pair of vertically positioned flat bars 187' (Fig. 3) arranged in front of the chute 5. These bars are movable up and down, their upper ends are guided through stirrups 188 fixed on the front wall of the chute 5 and their lower ends are hinged to horizontally extending bars 189 which extend back over the lines of packages and the rear ends of which are rigidly mounted on a transverse shaft 190 extending across the machine above the lines of packages. This shaft is oscillated to move the stop 187 up and down. The stop 187 is shown in its upper position in Figs. 3, 8, 9, and 10 and it is movable down from this upper position to a lower position where it is positioned in the path of the packages and behind the layer just inserted. To move the stop 187 up and down in timed relation to the insertion of the packages there is provided a suitable cam wheel 191 (Fig. 3) fixed on the shaft 38 which is engaged by a roller 192 carried on the end of a radius rod 193. The upper end of this rod is connected by a link 194 to the outer end of an arm 195 rigidly mounted on the shaft 190. The cam

is formed to drop the stop quickly just as the push bar 114 passes beneath the stop and to thus both hold the inserted packages from being dragged back and to hold back the next succeeding packages until the box with the layer just inserted has dropped down in position to receive the next successive layer or until the next box has dropped down to receive its first layer.

There is a certain resilience or springiness to the packages which may tend to force them back into contact with the rear wall of the chute as they drop free from the stop 187 and for the purpose of forcing and holding them back in the box and yet leaving them free to drop with the container when it drops, the front wall 196 of the chute beneath the entrance opening, (see Fig. 10) is mounted on hinges 197 at its lower edge so that it can swing back and forth on the top edge 198 of a lower fixed wall 199 of the chute which is beveled off so that the boxes cannot catch thereon as they drop down the chute.

The swinging part 196 of the wall of the chute is normally held at its outer position by a spring 200, and it is pushed inwardly by a projection 201 on a swinging lever 202 which is pivotally mounted on the frame at its lower end. This lever 202 has a projection 203 at its upper end which is engaged by the packing bar 114 as same starts back after pushing a layer into the box. By this means the lever 202 is swung backward. The lever 202 is connected between its ends by a link 204 to an upstanding lever 205 (Fig. 1) between its ends. The lever 205 is pivotally mounted at its lower end on the outer end of a rigid bracket 206 to swing in a vertical plane. The lever 205 is divided; that is, it is duplicated at each side of the frame and the upper ends of the two parts are connected to the package guide 177 by links 207 which engage the projections 184 of the package guide. As the package guide is moved forward by the packing bar 114 engaging with the shoulders 183 the mechanism just described is swung forward thus swinging the lever 202 forward and closing in the swinging plate 196 and moving its upper end inwardly out of the path of the packing bar 114 as the same moves downwardly at the inner end of its travel. Then the packing bar 114 engages the lever 202 and swings the whole mechanism backward thus through the links 207 pulling back the package carrier 177 free of the chute to permit the box being filled to drop free of same.

After the packages pass under the control rollers 166 in approaching the machine they might tend to tip up and in fact the packing bar 114 in rising into the path of the packages actually lifts the forward ends of the packages which follow the layer about to be

engaged, as it rises into alignment with the layer to push it forward. In order to force the following packages down again onto the package carrier there is provided a rigid inclined guide plate 208 in position so that as the packages move forward to follow the packing bar 114 in its forward movement they are forced downwardly.

5 The levers 165 and 167 upon which the 10 control rollers 166 are carried are provided with stops 209 on their undersides which limit their drop when no packages are beneath the rollers 166 thus preventing any undue strain to the stop mechanism.

15 As many modifications of my invention will readily suggest themselves to one skilled in the art I do not limit or confine my invention to the specific details of construction and operation herein shown and described.

I claim:

1. In a packing machine of the kind described, a chute down which boxes descend, means for dropping the boxes step by step to receive layers of articles, an article inserting mechanism arranged to insert a complete layer of articles at a time, said inserting mechanism arranged to permit the articles for the next succeeding layer to follow towards the box, and means for limiting the forward movement of the succeeding layer until the box has dropped sufficiently to admit same.

2. In an article packing machine of the kind described, means for dropping a packing box down a chute step by step to receive successive layers of articles, means for accumulating articles in position to be moved forward into the box, means for selecting a sufficient number of articles to form a layer and forcing the layer into the box, said means permitting the succeeding articles to follow toward the box, stop mechanism operable to hold back the successive articles until the next successive layer is selected.

3. In an article packing machine of the kind described, a chute down which boxes descend step by step to receive successive layers of articles, means for accumulating a plurality of rows of articles to form a continuing layer thereof of a width to enter the box, means for dividing off sufficient articles to form one layer in the box and for forcing such divided off articles into the box, said means permitting the advancement of succeeding articles to follow such divided off articles towards the box, and stop mechanism operable to hold back such succeeding articles until said layer selecting means has selected the succeeding layer.

4. An article packing machine of the kind described in combination with a conveyer belt for delivering articles to the machine, a horizontal chute along which the articles are moved into packing position, means on the

machine for making the conveyer effective for pushing the articles through said chute, machine stop mechanism operatively connected with said means and operable on the line of approaching articles.

5. In a packing mechanism of the kind described, a conveyor for delivering articles to a packing machine a horizontal chute into which the conveyor is adapted to direct the articles, means for pressing the articles upon the conveyor to cause the articles to be pushed into said chute, means for stopping the packing mechanism controlled by said pressure means and adapted to stop the packing mechanism upon the failure of the so approaching line of articles.

6. In an article packing machine, means for delivering articles to the machine in a continuous line, a gravity operated lever arranged above the path of delivery, and means operable by the lever when it drops, because of a break in the line of articles, for stopping the machine.

7. In an article packing machine, a conveyor for delivering articles in a line into position to be inserted into a box, a gravity operated lever arranged above the line of delivery of the articles and adapted to be supported by the articles, a driving shaft for the machine, a clutch operatively interposed between said lever and said shaft and adapted to be set by the lever to apply power to the machine when the lever is lifted by the line of articles and to unclutch the power shaft when there is a break in the line of the articles.

8. In an article packing machine, a conveyor for delivering articles in a line into position to be inserted into a box, a vertically swinging lever positioned to rest at its free end on the articles, a power shaft for the machine, a clutch for operatively connecting the shaft to the machine, the clutch being arranged to be clutched and unclutched by power from said shaft, a clutch shifter, and operative connection between said lever and said clutch shifter whereby, when the lever is raised by an article, the shifter is set to cause the power shaft to be clutched to the machine, and when the lever is not held up by an article the shifter is set to cause the shaft to be unclutched from the machine.

9. In an article packing machine, conveyor means for delivering articles in a plurality of lines, a power shaft for the machine, clutch means for operably connecting the shaft to the machine, a vertically swinging lever arranged above each line of articles, and means interposed between said levers and the clutch whereby the clutch is operated to disconnect the shaft upon a break in either line and to reestablish such connection upon the completion of all of the lines.

10. In an article packing machine, means

- for conveying articles in a plurality of lines into position to be placed, a vertically swinging lever above each line of delivery and adapted to be supported by the articles, a power shaft for the machine, a clutch for operatively connecting the shaft to the machine, the clutch arranged to be clutched and unclutched by power from said shaft, a clutch shifter, and operative connection between said levers and said shifter whereby, when any one of the several levers is not held up by the articles, the shifter is set to cause the power shaft to be unclutched from the machine, and when all of the levers are held up by the articles the shifter is set to cause the power shaft to be clutched to the machine.
11. In an article packing mechanism a horizontal chute in which to accumulate articles to be packed, antifriction rollers forming the floor of said chute, means for rotating said rollers for carrying the articles forward, means operable in conjunction with the rollers for inserting a layer of articles into a box and means for stopping the operation of said rollers and inserting means at times when the approaching articles are not continuous and for starting said operation again when succeeding articles are delivered.
12. In a machine of the kind described, a horizontal chute having anti-friction rollers forming its floor, means for pushing articles into said chute, the rollers being operable to assist the forward movement of the articles, chain belts operable in conjunction with said rollers, a transversely extending article pusher carried by said chains, said pusher adapted to enter the chute from below and engage the rear end of a layer of articles, said pusher adapted to temporarily lift the next succeeding articles out of its path in the layer engaging action.
13. In a machine of the kind described, a horizontal chute having anti-friction rollers forming its floor, means for pushing articles into said chute, the rollers being operable to assist the forward movement of the articles, chain belts operable in conjunction with said rollers, a transversely extending article pusher carried by said chains, said pusher adapted to enter the chute from below and engage the rear end of a layer of articles, said pusher adapted to temporarily lift the next succeeding articles out of its path in the layer engaging action, and means for forcing said temporarily lifted articles back into line as they are pushed forward.
14. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise past the rear roller of the series and engage behind an assembled layer of articles on the rollers and carry them forward into a box.
15. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise past the rear roller of the series and engage behind an assembled layer of articles on the rollers and carry them forward into a box, 70
16. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise past the rear roller of the series and engage 75
17. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 80
18. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 85
19. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 90
20. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 95
21. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 100
22. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 105
23. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 110
24. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 115
25. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 120
26. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 125
27. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers, said pusher adapted to rise 130

- mounted on toothed wheels at the ends of the end rollers of the series, an article pusher carried by said chains and adapted to sweep over said rollers, said pusher adapted 5 to rise past the rear roller of the series and engage behind an assembled layer of articles on the rollers and carry them forward into a box, and means for automatically stopping said rollers and pusher upon the failure of 10 the continuous assembly of the articles to be packed, said stopping means being also manually operable.
20. In a machine of the kind described, a horizontal series of rollers adapted to deliver articles to a box to be packed, the rollers adapted to be rotated, a pair of chains mounted on toothed wheels at the ends of the end rollers of the series, an article pusher carried by said chains and adapted to sweep over said rollers said pusher adapted 15 to rise past the rear roller of the series and engage behind an assembled layer of articles on the rollers and carry them forward into a box, a lever adapted to be lifted by the 20 articles as they approach, to start the packing mechanism, and to automatically drop and stop the packing mechanism when not held up by an article.
21. In a machine of the kind described, a horizontal series of rollers adapted to deliver articles to a box to be packed, the rollers adapted to be rotated, a pair of chains mounted on toothed wheels at the ends of the end rollers of the series, an article pusher 25 carried by said chains and adapted to sweep over said rollers, said pusher adapted to rise past the rear roller of the series and engage behind an assembled layer of articles on the rollers and carry them forward into a box, a machine starting element having an end 30 normally in the path of the approaching articles and adapted to be moved out of said normal position and to start the packing mechanism by the articles as they are fed past same and to automatically move back to 35 normal position and stop the mechanism upon the failure of the continuous line of approaching articles.
22. In a machine of the kind described, a chute down which boxes are adapted to descend past a packing mechanism, said boxes having flaps adapted to be turned back to present an open side to the packing mechanism, one of said flaps being on the lower 40 side and adapted to swing back into the plane of the open side of the box when released by the removal of the preceding box from the chute, and means in the path of the box at the lower part of the chute for folding back said lower flap.
23. In a machine of the kind described, a horizontal chute for receiving boxes with turned back flaps for presenting an open side to packing mechanism, a vertical chute 45 for receiving the boxes from the horizontal chute, and swinging lever pivotally mounted above the vertical chute, its free end depending within the chute and adapted to engage a flap on the forward side of the box before same is released by the next preceding 50 box as it descends the vertical chute.
24. In a machine of the kind described, a horizontal chute for receiving boxes with turned back flaps for presenting an open side to packing mechanism, a vertical chute 55 for receiving the boxes from the horizontal chute, and pendulum like lever pivotally mounted above the vertical chute, its free end adapted to engage a flap on the forward side of a box before the same is disengaged 60 by the next preceding box as it descends the vertical chute.
25. In a machine of the kind described, a vertical chute down which packing boxes descend past a packing mechanism, gate 65 means at the lower end of said chute for permitting the exit of a filled box, means for lowering the box step by step to receive successive layers of articles, and means operable by the lowering mechanism for opening the gate means as the filled box descends the last step.
26. In a machine of the kind described, a vertical chute down which packing boxes descend past a packing mechanism, the 70 lower part of the chute being open at one side to permit the escape of a filled box, guard means for said open side normally preventing the escape of a box, said guard means being adapted to be moved to permit the escape of a filled box by the box lowering mechanism as the box reaches its lowermost position.
27. In a machine of the kind described, a vertical chute down which packing boxes descend past a packing mechanism, a conveyor mechanism forming part of the machine at the lower end of the chute for pushing a filled box out of the chute and a conveyor adapted to receive the box as it is 75 pushed out.
28. In a machine of the kind described, a vertical chute down which packing boxes descend past a packing mechanism, means entering the chute from the side opposite to the packing mechanism to hold up an empty box for receiving the first layer, and means for withdrawing said supporting means after the first layer is inserted to permit the box to descend for the second layer.
29. In a machine of the kind described, a vertical chute down which boxes descend past a packing mechanism, means for permitting a box to descend step by step to receive successive layers, means entering the 80 side of the chute opposite to the packing mechanism to support the box at suitable height to receive the first layer, means operable by the box control mechanism for withdrawing said support after the first 85

layer is inserted, said support means being adapted to re-enter the chute when a filled box drops past same.

30. In a machine of the kind described, a vertical chute down which boxes descend past a packing mechanism, means for permitting a box to descend step by step to receive successive layers, means entering the chute to support the box at suitable height to receive the first layer, means for withdrawing said support after the first layer is inserted, said means being adapted to enter the chute when a filled box drops past same, and other means adapted to enter the front of the chute above the packing mechanism for holding the box up to receive the first layer.

31. In a machine of the kind described, a vertical chute down which boxes descend past a packing mechanism, means for permitting a box to descend step by step to receive successive layers, means entering the chute to support the box at suitable height to receive the first layer, means for withdrawing said support after the first layer is inserted, said means being adapted to enter the chute when a filled box drops past same, and other means adapted to enter the front of the chute above the packing mechanism for holding the box up to receive the first layer, and means for withdrawing both said supports after the first layer has been inserted.

32. In a machine of the kind described, a vertical chute down which packing boxes descend past a packing mechanism, a support member spanning said chute adapted to receive a box after it has received the first layer, means for permitting said support member to descend step by step for the insertion of additional layers, said member having an antifriction roller upon which the box rests and which permits the easy ejection of a filled box.

33. In a machine of the kind described, a vertical chute down which packing boxes descend past a packing mechanism, a support member spanning said chute adapted to receive a box after it has received the first layer, means for permitting said support member to descend step by step for the insertion of additional layers, said member having an antifriction roller upon which the box rests and which permits the easy ejection of a filled box, and means for lifting said member to the upper limit of its movement upon release from a filled box.

34. In a machine for inserting articles layer by layer into a packing box, a layer guide having a bottom at its forward end and insertable with a layer into a box to guide the articles freely over preceding layers, the rear part of the guide being without

a bottom and carrier rollers arranged to move the articles forward into the forward end of the guide.

35. In a machine of the kind described, an article guide insertable into a packing box with a layer of articles, a layer pusher for pushing a layer into the box shoulders on the guide for engagement by the pusher for moving the guide forward with a layer, and means engageable by said pusher on its return movement for withdrawing the guide from the box.

36. In a machine for packing articles in a box, mechanism for inserting the articles layer by layer, mechanism for dropping the box step by step to receive the layers, and means for engaging an inserted layer as the box drops and forcing it into normal proper position.

37. In a machine for packing articles in a box, a chute down which the boxes drop step by step past a packing mechanism to receive successive layers, the wall of the chute below the packing mechanism being movable in and out to control the articles and to permit the box to drop freely.

38. In a machine for packing articles in a box in horizontal layers means for dropping a box step by step for receiving successive layers, means for assembling the articles in successive layers which immediately follow each other, means for inserting one layer after another into a box, stop means for engaging the inserted layer to prevent its withdrawal, said stop means also limiting the forward movement of the next assembling layer until the box has dropped to receive same.

39. In a machine of the kind described, a vertical chute down which packing boxes descend past a packing mechanism, the lower part of the chute being open at one side to permit the escape of the filled boxes, guide bars partially closing said open side and preventing the escape of the boxes, and means operable by the box control mechanism as the box reaches the bottom of the chute for swinging said guide bars to permit the box to escape.

40. In a machine of the kind described, a vertical chute down which packing boxes descend past a packing mechanism, hooks adapted to enter the chute on the side opposite to the packing mechanism to support the box in position to receive the first layer, means for controlling the descent of the box after receiving the first layer, and means operable by the box control means for withdrawing said hooks after the insertion of the first layer.

In testimony whereof, I have hereunto set my hand, this 28th day of August, 1925.
EDDY T. MCKAIG.
